ATTORNEY

UNITED STATES PATENT OFFICE.

DANIEL HALL, OF GAULT, MISSOURI.

CAR BRAKE AND STARTER.

SPECIFICATION forming part of Letters Patent No. 339,645, dated April 13, 1886.

Application filed August 3, 1885. Serial No. 173,453. (No model.)

To all whom it may concern:

Be it known that I, DANIEL HALL, a citizen of the United States, residing at Gault, in the county of Grundy and State of Missouri, have 5 invented certain new and useful Improvements in Car Brakes and Starters, of which the following is a specification, reference being had therein to the accompanying drawings.

10 My invention is particularly adapted to horse-cars; and it consists in a novel construction, arrangement, and operation of devices for stopping a car and for storing power to assist in starting, as hereinafter more particularly described.

15 In the accompanying drawings, Figure 1 is a top view of a mechanism embodying my improvements. Fig. 2 is a view of one of the axles and devices attached thereto. Fig. 3 is 20 a vertical section taken in the line $x-x$ of Fig. 2. Fig. 4 is a vertical section taken in the line $y-y$ of Fig. 1. Figs. 5, 6, 7, and 8 are detail views.

A represents the axle, and B the wheels, of 25 a horse-railway car. Surrounding the axle, extending part of its length, is a sleeve, C, provided near its ends with oil cups or holes and suitable bearings, and having its intermediate interior surface grooved or concave, so as to allow 30 free circulation of oil between the sleeve and the axle. Near one end of the sleeve is a drum, D, formed of two disks connected by rods or bars surrounded by a band or tire. In this drum is a coiled spring, E, the outer end 35 of which is attached to one of the rods or bars of the drum, and the inner end is attached to the sleeve C. Between one end of the drum and the contiguous end of the axle is a disk, G, which is keyed to the car-axle so 40 as to turn with it. In the inner face of this disk is a series of acute depressions or pockets, g , and the corresponding face of the end of the drum is provided with spring-pawls d , for engagement with said acute depressions or 45 pockets. On the opposite end of the sleeve, attached to or forming a part of the drum, is a disk, H, having obtuse holes or pockets f in its outer face. Between this disk and the end 50 of the axle is a disk, J, which is feathered to the axle so as to turn with it. The inner face

of this disk is provided with obtuse pawls i , for engagement with the obtuse holes or pockets f in the disk H.

Between the disks H and J is an intermedial disk, I, provided with holes through which 55 the bolts i' and pawls i pass to engage with the holes or pockets f . These two disks H and J form a clutch, and the two parts are thrown into engagement by a forked lever, K, the front end of which rests in a frame at the 60 front end of the car, and the other end is suitably secured by hinge or pivot joint. A spring, h , has a tendency to press the lever outward.

Instead of the clutch above described, the 65 ratchet-toothed form of clutch shown in Fig. 5 may be used.

On the inner side of the disk H is a series of notches, h , (see Fig. 6,) for engagement with a pawl, L, pivoted to the sleeve C, and provided with two springs, $l m$, one for engaging it with the notches h and the other for disengaging it. To the pawl L is attached one end of a cord or chain, M, which passes around pulleys, and has its other end attached to the 75 lever K.

X is a frame composed of curved pieces x' and x'' , extending over the axles, and properly journaled to the same with pieces x^3 and x^4 , connecting them together from front to rear. 80

From the under side of the rear portion of the frame X extends a hanger, p , to which is pivoted the rear end of a clamping-brake consisting of two rigid strips or bars, P P, which are curved to embrace the upper and lower 85 surfaces of the band or tire s' of the drum D, and which have a spring, q , between them to keep them disengaged from the tire s' when not in use. The front ends of these bars are passed through a compressing device, Q, consisting of two rectangular frames pivoted together somewhat after the manner of a saw-buck. The upper end of one of the frames is hinged or pivoted to the under side of the platform or frame X, and the lower end of the 90 other frame has attached to it a cord or chain, R, which passes over a pulley and is attached to the brake-operating crank-handled brake-shaft T.

To the lever K, between the fulcrum and the 95

outer end, is attached one end of a cord or chain, S, which passes around a pulley and is attached to the brake-shaft, T.

The parts being thus constructed and arranged, when the brake-shaft T is turned the rod, link, or chain R and S is wound around two shafts simultaneously. By this means the clamping-brake P is compressed, so as to bear on the upper and lower surfaces of the band or tire of the drum D. At the same time the action of the lever K throws the clutch J into engagement and winds up or compresses the spring E, while the slackening of the cord or chain M allows the spring m to engage the pawl L with the notches h and prevent the spring E from unwinding, and the car is brought to a full stop. When the brake-shaft is turned in the opposite direction, the spring k throws the lever K outward and disengages the clutch, and the unwinding of the spring E turns the axle and assists in starting the car by turning the drum D forward. The pawls d, engaging the pockets in the disk G, turns forward the axle and starts the car.

Figs. 7 and 8 represent an alternative device for operating the mechanism by the brake-shaft T. On the platform of the car rests a gear-wheel, V, through which the brake-shaft T passes loosely. Keyed or otherwise attached to the shaft T is a double ratchet-wheel, v, and on the gear-wheel V is a double-acting pawl, v². When the pawls are not engaged with the ratchet, the shaft turns without turning the wheel; but when the pawls and ratchet are engaged the wheel turns with the shaft. The pawls are disengaged by pulling them backward and holding them by means of a plate, v³, which is provided with a hole for engagement with a pin on the pawl.

Adjoining the wheel V and gearing with it is a gear-wheel, W, attached to the upper end of a shaft, to which the cord or chain S is connected. When the pawls v² and ratchet v are engaged so as to turn the wheel V, the wheel

W is also turned, so as to wind up the cord or chain S, and thus the parts are operated simultaneously.

The shaft may be made square in its upper portion for the engagement with a suitable crank when desired.

What I claim as new, and desire to secure by Letters Patent, is—

1. In a car brake and starter, the combination, with the axle, the sleeve, and drum carrying the helical spring, of the disk G, keyed to the axle and provided with depressions or pockets g, for engagement with the spring-pawls d, as shown and described, for the purpose specified. 55

2. The combination, with the disk J, of the lever K, spring k, cord or chain S, and the brake-shaft T, as shown and described, for the purpose specified.

3. The combination, with the sleeve C and the disk H, provided with the notches h, of the pawl L, springs l m, cord or chain M, and lever K, as shown and described, for the purpose specified. 65

4. The combination, with the compressing clamp or brake P, of the compressing-frame Q, cord or chain R, and brake-shaft T, as shown and described, for the purpose specified.

5. The combination of the brake-shaft T with the cord or chain R and connected devices, and the cord or chain S and connected devices, as shown and described, for the purpose specified. 75

6. The combination, with the brake-shaft T and connected devices, of the gear-wheels V W, the double ratchet v, the pawl v², and the adjusting-plate v³, as shown and described, for the purpose described.

In testimony whereof I affix my signature in presence of two witnesses.

DANIEL HALL.
